11 Claims. (Cl. 126—59.5)

1

This invention relates to a smoke generator for use in producing smoke for the smoke curing or preserving of comestibles, such as meat and fish, and to a novel method of generating such smoke.

Smoke generators now available produce smoke of varying density with consequent variation in the color and other properties of the comestibles cured or preserved by treatment therewith. Moreover, such smoke generators are relatively inflexible, i. e., they can be operated at full capacity or not at all. In those cases in which a smoke generator is employed to supply smoke for a plurality of smoke houses and for some reason it is desired to supply smoke to only some of the houses, the inflexibility of the smoke generator presents a serious problem. Usually the smoke generator is run at its full capacity and the smoke supplied to the smaller number of smoke houses; under these conditions comestibles are subjected to a correspondingly greater volume of smoke with consequent deleterious effect on the product and uneconomic utilization of the sawdust employed to produce the smoke.

Among the objects of this invention is to provide a smoke generator which produces a smoke stream of substantially constant density and which is relatively flexible so that it can produce a desired amount of smoke of substantially constant density per unit of time for use in one or more smoke houses and this with economic consumption of the sawdust employed to generate the smoke.

Another object of this invention is to provide a novel method of generating smoke suitable for use in curing or preserving comestibles, which method results in the production of a maximum amount of smoke of substantially constant density and relatively free of tarry constituents per unit amount of sawdust consumed.

Other objects and advantages of this invention will be apparent from the following detailed description thereof.

In accordance with this invention a stream of air, preferably under pressure, is introduced into a bed of sawdust and caused to flow first in a generally vertical direction throughout substantially the full depth of this bed, the air supporting combustion of the sawdust and causing smoldering thereof to take place to produce smoke. The smoke thus produced is passed through a horizontal path extending below the surface of the bed of sawdust, whereby tarry constituents are removed from the smoke. The thus filtered smoke is removed from the bed. Desirably the air is introduced into the upper por-

2

tion of the smoke generator at a plurality of spaced points along the width of this generator under superatmospheric pressure of the order of 2 to 14 ounces per square inch gauge, is passed downwardly through the full depth of the bed of sawdust and upon reaching the base of the generator passed in a generally horizontal direction through the main bed of sawdust. Operation in this manner effects efficient distribution of air throughout the sawdust in amount to cause smoldering of the sawdust to take place to produce smoke, and insures the substantially complete utilization of the sawdust to produce smoke. Further the flow of the smoke thus produced through the main bed of sawdust prior to its discharge from the smoke generator causes the smoke to be filtered by this bed of sawdust before leaving the generator thus removing from the smoke tarry constituents and particles of ash and dust.

In accordance with a preferred embodiment of the invention, the smoke generator comprises a horizontally elongated housing having baffles disposed near the ends defining vertically extending air inlet and smoke exit chambers positioned at the opposite ends of the housing and a horizontally elongated intermediate chamber. A bed of sawdust which may be hickory or other wood dust or chips is disposed in the air inlet and intermediate chambers; the smoke exit chamber is substantially free of sawdust. Air is supplied to the smoke generator from a main air stream of substantially constant volume per unit of time, which volume, however, can be adjusted in accordance with the amount of smoke desired; thus, if the generator is employed to supply two smoke houses of equal capacity, the volume of air per unit of time constituting this main air stream would be twice the volume employed to generate smoke for a single such smoke house. This main air stream is divided into two streams, one of which by-passes the body of sawdust, and the other is introduced into the air inlet chamber to support combustion of sawdust therein, the air being admitted in amount to cause smoldering of the sawdust in this chamber and the intermediate chamber to take place to produce smoke. The smoke thus generated is passed through the bed of sawdust in the intermediate chamber below the surface thereof thereby effecting the removal of tarry constituents, ash and dust, from the sawdust. The thus filtered smoke then enters the smoke exit or discharge chamber. From this discharge chamber the smoke enters a smoke main into which also flows the by-passed air pro-

ducing the desired smoke stream which is fed to one or more smoke houses.

The division of the main air stream into the aforesaid two streams is regulated to produce a desired smoke stream of substantially constant density. The regulation preferably is carried out by a control involving a pair of temperature responsive elements, one positioned in the air stream leading into the air inlet chamber and the other in the smoke exit line leading into the smoke main where the smoke and by-passed air mix. These temperature responsive elements measure the temperature differential between the temperature of the entering air and the exiting smoke and communicate with a controller which effects operation of valves controlling the flow of air through the air inlet line and the by-pass line. Alternatively a photo-electric cell may be disposed in position to intercept a beam of light passing through the smoke main supplying the lines leading to the smoke houses; and the photo-electric cell communicably connected with a control for operating the aforesaid valves in the air inlet and by-pass lines to regulate the division of the constant volume main air stream into two streams (one supplied to the smoke generator to support combustion of sawdust and the other by-passed about the generator and mixed with the smoke generated) to maintain the density of the product smoke stream substantially constant.

I have found that as a general rule variations in the density of the smoke are proportional to variations in the temperature differential between the temperature of the smoke leaving the generator and the temperature of the air entering. By supplying a substantially constant volume of air for the production of a desired given amount of smoke and dividing this air stream into two streams, one of which by-passes the bed of sawdust and the other of which is introduced into the bed of sawdust to support combustion thereof to produce smoke and regulating the division of this main air stream in accordance with variations in the temperature differential between the temperature of the entering air and the exiting smoke so as to restore this differential to a predetermined value, a smoke stream of constant density is produced. This smoke stream may be employed to cure or preserve comestibles producing smoked products, the color and other properties of which are markedly more uniform than smoked products heretofore produced.

The optimum differential value for which the control may be set is dependent upon the nature of the sawdust and the capacity and design of the smoke generator. For any particular generator and type of sawdust consumed therein this value may readily be determined by an initial trial run.

In the accompanying drawings forming a part of this specification and showing for purposes of exemplification preferred forms of this invention without limiting the claimed invention to such illustrative instances:

Figure 1 is a plan view of a smoke generator embodying a preferred form of this invention;

Figure 2 is a vertical section taken in a plane passing through line 2-2 of Figure 1;

Figure 3 is an end elevational view of the smoke generator of Figures 1 and 2;

Figure 4 is a rear elevational view of the smoke generator and shows a photo-electric cell type of control for actuating the valves in the air inlet and by-pass lines instead of the tempera-

ture differential control shown in Figures 1 to 3; and

Figure 5 is a detail view showing a section through the smoke main and a perspective view of the photo-electric cell for receiving light rays from a beam of light passing through the smoke main.

In the drawings 10 indicates a smoke generator housing which may be in the form of a rectangular box having metal walls, desirably cast iron or steel. Fire brick or other refractory support 11 is provided in the base of this housing for supporting a bed of sawdust. Instead of a solid fire brick support, a grate may be employed disposed above the base of the housing, through which grate ash may fall into the base of the housing for ready removal. However, the solid fire brick support which can be cleaned from time to time to remove ash and tarry deposits thereon is preferred. The side and end walls of this housing are lined with suitable heat insulating material, such as the asbestos cement composition known as Transite; this lining is indicated by the reference character 12.

Suitably secured to the top of the housing near the opposite ends thereof are baffle members 13, 14 extending downwardly from the top to a point above the fire brick support 11. Baffle 13 extends across the width of the housing and cooperates with end wall 15 to define an air inlet chamber 16 extending in a generally vertical direction, i. e., chamber 16 has a somewhat greater vertical extent than the distance between baffle 13 and end wall 15. Baffle 14 is spaced from the opposite end wall 17 to define a smoke exit duct or chamber 18 extending in a generally vertical direction contiguous to the end wall 17. Baffles 13 and 14 define the end walls of an intermediate sawdust receiving chamber 19 which, it will be noted from Figure 2 of the drawings, extends in a generally horizontal direction. Positioned substantially midway between baffles 13 and 14 is a baffle 20 extending from the base of the housing to a point 21 positioned above the terminals of baffles 13 and 14. The baffles 13, 14, and 20 desirably are of asbestos cement material, such as Transite, or other fire resistant material.

Top 22 of the housing is provided with an access opening 23 closed by a suitable cover 24 through which sawdust may be charged into the housing 10 to produce a bed 25 resting on the refractory support 11 and disposed within the air inlet chamber 16, and intermediate chamber 19 leaving a free space 26 above this bed. An access opening 27 closed by a suitable cover 28 may be formed in the end walls 17 to give access to the smoke discharge chamber 18 for cleaning or other purposes when desired. Access openings 29, 30 provided with suitable closures are desirably formed in a front or rear wall of the housing near the base thereof to give access to the refractory support for cleaning or other purposes. Also an access opening 31 provided with a suitable closure may be formed in a front or rear wall near the top of the housing to give access to the top portion of the air inlet chamber 16 and the intermediate chamber 19; sawdust may be fed through access opening 31 into air inlet chamber 16 to produce a bed of sawdust in this chamber, as shown in Figure 2.

A blower 32 actuated by a multiple speed motor 33 supplies air to the generator. Blower 32 and motor 33 may be of any known type which, depending upon the selected speed of operation of the motor, supplies a predetermined

constant volume of air to the main air line 34 communicating with the blower. If the generator is designed for supplying smoke to four smoke houses, desirably a 4-speed motor is employed, the motor being operated at its maximum speed when all four houses are in operation and being operated at 1st, 2nd or 3rd speeds when 1, 2 or 3 smoke houses, respectively, are supplied with smoke from the generator. A manual control valve 35 in the main air line 34 is provided for controlling the volume of air delivered by the blower 32 to the main air line 34. This valve may be used with a single speed motor driven fan to control the volume of air delivered by the fan to the main air line; thus, if two smoke houses are supplied with smoke, the valve is set to give a flow per unit of time twice the volume of that employed when only one smoke house is supplied with smoke.

Main air line 34 communicates with two branches. One branch 36 constitutes the air inlet line supplying air to the air inlet chamber 16. This branch 36 has a plurality of spaced off-take pipes 37 each provided with a valve 38 and leading into the air inlet chamber 16 at spaced points, as indicated in Figure 1. The other branch 39 constitutes an air by-pass line which leads into a smoke main 40 communicating with the smoke distributing pipes or ducts in the smoke houses.

A butterfly valve 41 is positioned in the branch 36 and is arranged to be actuated by a motor 42 of any well known type through suitable linkage mechanism 43. A butterfly valve 44 is disposed in the by-pass branch 39 and is arranged to be actuated by a motor 45 of any well known type, desirably the same as that of 42, through the linkage mechanism 46. Valves 41 and 44 are normally positioned to divide the main air stream flowing through line 34 into the branches 36, 39 into two streams bearing a definite volume ratio to each other, one of the streams flowing through line 36, offtake pipes 37 into the air inlet chamber 16 and the other by-passing the smoke generator and flowing into the smoke main 40.

Smoke discharge chamber 18 is provided with a series of spaced offtakes 47, as shown in Figure 1, each provided with a valve 48 and leading into a smoke manifold 49 which communicates with the smoke main 40.

Disposed in air inlet branch 36 is a temperature control element 50 responsive to the temperature of the air entering the inlet chamber 16. A like element 51 is disposed in the smoke manifold 49 responsive to the smoke leaving the smoke generator. Elements 50, 51 are connected through conductors 52 with a differential thermostat or other control device 53, which, through conductors 54, effects operation of the motors 42, 45 actuating the valves 41, 44, respectively. The control involving the temperature responsive elements 50, 51, the differential thermostat 53, and the conductors 52 and 54 may be any well known type of controller such, for example, as the remote bulb differential temperature controller commercially available, the differential thermostat of which, for example, may effect opening or closing of electrical switches in circuit with the electric motors 42, 45, thereby energizing or de-energizing these motors to change the position of the butterfly valves 41 and 44 to cause more or less of the main air stream to flow through branch 36 and less or more of this main air stream, respectively, to flow through by-pass branch 39.

The density of the smoke generated will depend chiefly on the amount of air supplied to support combustion of the sawdust, the particle size of the sawdust, the moisture content of the sawdust, the character of the sawdust, i. e., whether hickory or other wood, the time of contact between the air and the sawdust particles, etc. These factors vary during the operation of the generator; thus successive charges of sawdust may have varying moisture contents. As the sawdust is consumed channeling of the air in its flow through the bed of sawdust may take place, the extent of channeling varying with consequent variation in the time of contact between air and sawdust, etc. Hence, as a practical matter it has not been possible with prior designs of smoke generators to produce smoke of substantially constant density.

With my invention, on the other hand, the speed of motor 33 driving blower 32 or valve 35, or both, is set to give a desired volume of air per unit of time, depending upon the amount of smoke desired per unit of time. Controller 53 is then set for a predetermined value, determined by a previous trial run for each particular generator and type of sawdust consumed therein to give a smoke of desired density. The temperature of the smoke entering manifold 49 is dependent chiefly upon the rate of combustion of the sawdust, the amount of sawdust consumed, and the temperature of the air introduced through branch 36. In effect, the division of the constant volume main air stream into two streams, one of which enters the smoke generator and the other by-passes this generator and is mixed with the generated smoke, is varied to maintain a substantially constant differential temperature between the temperature of the inlet air passing through branch 36 and the temperature of the exit smoke passing through branch 49 and thereby produce a desired volume of smoke per unit of time of substantially constant density. Thus, for example, if due to increase in the moisture content of the sawdust, less sawdust is consumed, producing a smoke of decreased density having a lower temperature, the control operates to increase the flow of air into chamber 16 and decrease the flow through by-pass branch 39 causing the generation of more smoke per unit of time with consequent increase in temperature. Similarly, if the temperature of the smoke flowing through line 49 increases for any reason, the control operates to cause less of the main air stream to flow through line 36 and more to flow through by-pass 39 with consequent lower consumption of sawdust per unit of time and the production of less smoke at a lower temperature. In effect, during operation the control functions to substantially continuously change the position of the butterfly valve 41, 44 so that whenever the differential temperature rises above the predetermined value it is brought down to this value and when it falls below this value it is brought up thereto, a constant volume of air flowing through main air line 34, more or less of the air being used to support combustion and less or more by-passed and mixed with the smoke generated to produce a desired volume of smoke product (diluted with air) per unit of time of substantially constant density.

Disposed at the base of the generator housing, just above the fire brick support 11 where the smoke discharge chamber 18 communicates with the intermediate chamber, is a thermostatic element 55, such as a pyrostat 55, which may be

of any well known type. Pyrostat 55 is located at the point where the last portion of the bed of sawdust will be burning when the bed is substantially completely consumed. It is in circuit through conductors 56 with motor 33 and through conductors 57 with a bell 58. Thus, should substantially all of the sawdust constituting the bed be consumed pyrostat 55 operates to shut off motor 33 operating fan 32 to discontinue supply of air to the smoke generator and to ring the alarm 58, thereby calling the operator's attention to the need for replenishing the bed of sawdust.

Sawdust may be fed to the generator from an automatic charging device supplying the sawdust through top opening 23, or top side opening 31, or both, so as to maintain a bed of sawdust at a desired level within narrow limits. If desired, the generator may be charged manually from time to time as required. The term "sawdust" is used herein in a broad sense and is intended to include wood chips and chips or dust of other cellulose material suitable for use in generating smoke for treating combustibles.

Instead of the differential temperature controller shown in Figure 1, 2 or 3, the photoelectric cell type of control, as shown in Figures 4 and 5, may be used. In Figure 5, 59 indicates a light source from which a beam of light 60 passes across main 48 and impinges on a photoelectric cell 61 of any well known type. This cell is in circuit with motors 42 and 45 which effect operation of valves 41 and 44. As the density of the smoke stream passing through main 40 varies, the density of the light beam 60 impinging on cell 61 varies correspondingly, causing this cell through suitable amplifiers and relays, as well known in the electrical control art, to effect operation of motors 42 and 45 to divide the main air stream into two streams of varying volume per unit of time. This division is such that more air is passed through the generator to generate more smoke when the density falls to restore the density to the desired value and less air is fed to the generator when the density of the smoke stream passing through main 40 rises to generate less smoke and restore the density to the desired value.

Thus it will be noted the smoke generator of this invention produces a smoke stream of substantially constant density. Further, it is flexible in operation since by suitable selection of motor speed driving the air supply fan or of the valve associated with this fan any desired volume of smoke may be generated of desired density to treat combustibles in any reasonable number of smoke houses for any desired treatment time. Thus with this invention four smoke houses may be supplied with a desired density smoke for say an eight hour process period and if it is necessary at some other time to supply only two of these houses with smoke, by halving the fan speed two such smoke houses can be supplied with the same density smoke for the same process period and this with the same economical consumption of sawdust.

With the baffle arrangement shown the air is caused to flow vertically through substantially the full depth of the bed of sawdust, and the smoke generated horizontally below the surface of the horizontally elongated bed so that the smoke is filtered, resulting in the production of relatively clean smoke, i. e., smoke containing little or no ash, dust and tarry constituents. This smoke, if desired, may be subjected to a water

scrubbing treatment by passage through a chamber in which it is scrubbed with water to produce a still cleaner smoke; for example, the smoke stream from main 40, before entering the smoke distributing pipes or ducts, may be passed through a water scrubber. The introduction of air under pressure, its distribution as hereinabove described, and the flow of the generated smoke through the bed of sawdust results in the most effective utilization of the sawdust to generate smoke.

The introduction of the air under pressure in a downward direction in a bed of sawdust supported on a solid fire brick support, as in the preferred embodiment of this invention, avoids agitating the bed so as to cause suspension of the sawdust particles in the air stream with more effective utilization of the sawdust to generate smoke. The flow of this smoke containing uncombined or unreacted oxygen through the bed in a horizontal direction effects cleaning of the smoke as hereinabove described and also most effective utilization of the sawdust to generate smoke.

For initial lighting of the sawdust, a small gas burner may be installed at the surface of the bed of sawdust in the air inlet chamber. When this chamber is filled with sawdust, as indicated in the drawing, this burner is lit and the air thereafter caused to enter this chamber. Thereafter, the supply of gas to this burner is interrupted, the smoldering sawdust heating the incoming air and causing this air to support combustion of additional sawdust to generate smoke.

Since certain changes in carrying out the above process and in the smoke generator, which embody the invention, may be made without departing from its scope, it is intended that all matter contained in the above description or shown in the accompanying drawing shall be interpreted as illustrative and not in a limiting sense.

What is claimed is:

1. The method of producing a smoke stream of substantially constant density for treating combustibles, which comprises flowing a main stream of air of substantially constant volume per unit of time, dividing said stream into two streams, flowing and regulating the quantity of one of the two streams in contact with a body of sawdust to support incomplete combustion of said sawdust and produce smoke, by-passing the other of said two streams about the said body of sawdust, mixing the said smoke with the by-passed air stream to produce a smoke stream, and regulating said division of said main air stream to maintain the density of said smoke stream substantially constant and produce a smoke stream of predetermined constant density.
2. The method of producing a smoke stream of substantially constant density for treating combustibles, which comprises flowing a main stream of air of substantially constant volume per unit of time, dividing said stream into two streams, introducing and regulating the quantity of one of the two streams in contact with a body of sawdust to support incomplete combustion of said sawdust and produce smoke, withdrawing the said smoke, by-passing the other of said two streams about said body of sawdust, mixing the withdrawn smoke with the bypassed air stream to produce a smoke stream, and regulating said division of said main air stream in accordance with variations in the temperature differential

between the temperature of air introduced into contact with the said body of sawdust and the temperature of the said withdrawn smoke to maintain the density of said smoke stream substantially constant.

3. The method of producing a smoke stream of substantially constant density for treating comestibles, which comprises flowing a main stream of air of substantially constant volume per unit of time, dividing said stream into two streams, flowing and regulating the quantity of one of said two streams into a horizontally elongated bed of sawdust, directing said air to travel in a generally vertical direction throughout substantially the full depth of said bed to support incomplete combustion of said sawdust and cause smoldering thereof to take place to produce smoke, passing said smoke through a horizontal path extending below the surface of said bed, whereby tarry constituents in said smoke are removed therefrom, withdrawing the thus filtered smoke from the bed, by-passing the other of said air streams about the said bed of sawdust, mixing the by-passed air stream with the said filtered smoke stream to produce a smoke stream, and regulating said division of said main air stream to maintain the density of said smoke stream substantially constant, and produce a smoke stream of predetermined constant density.

4. The method of producing a smoke stream of substantially constant density for treating comestibles, which comprises flowing a main stream of air of substantially constant volume per unit of time, dividing said stream into two streams, introducing one of said streams into the top of a horizontally elongated bed of sawdust, directing said air to travel in a generally downward direction throughout substantially the full depth of said bed at one end thereof and regulating the quantity thereof to support incomplete combustion of said sawdust and cause smoldering thereof to take place to produce smoke, passing said smoke through a horizontal path extending below the surface of said bed of sawdust from the said one end to the other end thereof, whereby the tarry constituents in said smoke are removed therefrom, withdrawing the thus filtered smoke from the other end of said bed, by-passing the other of said air streams about the said bed of sawdust, mixing the by-passed air stream with the said smoke stream withdrawn from said bed to produce a smoke stream, and regulating the said division of said main air stream in accordance with variations in the temperature difference between the temperature of the said stream of air introduced into said bed and the temperature of said filtered smoke withdrawn from said bed to produce a smoke stream consisting of the smoke generated mixed with the by-passed air stream of substantially constant density.

5. The method of producing a smoke stream for treating comestibles, which comprises flowing a stream of air into a horizontally elongated bed of sawdust, directing said air to travel in a generally vertical direction throughout substantially the full depth of said bed at one end thereof and regulating the quantity thereof to support incomplete combustion of said sawdust and cause smoldering thereof to take place to produce smoke, passing said smoke through a horizontal path extending below the surface of said bed from the first mentioned end of the bed to the other end, whereby tarry constituents in said smoke are removed therefrom, and withdrawing the

thus filtered smoke from the other end of said bed.

6. The method of producing a smoke stream for treating comestibles, which comprises introducing a stream of air under pressure into the top of a horizontally elongated bed of sawdust at one end thereof, directing said air to travel in a generally downward direction at said end throughout substantially the full depth of said bed and regulating the quantity thereof to support incomplete combustion of said sawdust and cause smoldering thereof to take place to produce smoke, passing said smoke through a horizontal path extending below the surface of said bed of sawdust from the said end thereof to the opposite end, whereby the tarry constituents in said smoke are removed therefrom, and withdrawing the thus filtered smoke from the said opposite end of said bed.
7. A smoke generator comprising a housing, a support in said housing for a bed of sawdust, baffles in said housing disposed near the ends thereof defining an inlet chamber near one end of the housing, a smoke discharge chamber near the opposite end of the housing and an intermediate chamber, said bed of sawdust being disposed in said inlet and intermediate chambers, means for introducing air into the air inlet chamber and for regulating the quantity thereof to support incomplete combustion of said sawdust and causing smoldering thereof to take place to produce smoke and for passing said smoke through the bed of sawdust in the intermediate chamber, and means for withdrawing the smoke from the smoke discharge chamber.
8. A smoke generator comprising a horizontal elongated housing, a support in the base of said housing for a bed of sawdust, baffles extending from the top of said housing into said bed of sawdust near the opposite ends of said housing and terminating short of the said support defining a vertically elongated air inlet chamber, a vertically elongated smoke discharge chamber, and a horizontally elongated intermediate chamber, a baffle extending from the base of said housing intermediate the first mentioned baffles to a point above the point of termination of said first mentioned baffles, and means for introducing air under pressure into the air inlet chamber and for regulating the quantity thereof to support incomplete combustion of said sawdust and cause smoldering thereof to take place to produce smoke and for passing said smoke through the bed of sawdust in said intermediate chamber into said smoke discharge chamber, and means for withdrawing the smoke from the smoke discharge chamber.
9. A smoke generator comprising a horizontal elongated housing, a support in the base of said housing for a bed of sawdust, baffles extending from the top of said housing into said bed of sawdust near the opposite ends of said housing and terminating short of the said support defining a vertically elongated air inlet chamber, a vertically elongated smoke discharge chamber, and a horizontally elongated intermediate chamber, a baffle extending from the base of said housing intermediate the first mentioned baffles to a point above the point of termination of said first mentioned baffles, means for introducing air under pressure into the air inlet chamber and for regulating the quantity thereof to support incomplete combustion of said sawdust and cause smoldering thereof to take place to produce smoke and for passing said smoke through the

bed of sawdust in said intermediate chamber into said smoke discharge chamber, means for withdrawing the smoke from the smoke discharge chamber, means for flowing a stream of air bypassing said housing, means for mixing said bypassed air with the said smoke withdrawn from the smoke discharge chamber and control means for maintaining the mixture at a substantially constant density.

10. A smoke generator comprising a housing, a support in said housing for a bed of sawdust, baffles in said housing disposed near the ends thereof defining an air inlet chamber near one end of the housing, a smoke discharge chamber near the opposite end of the housing and an intermediate sawdust containing chamber, a main air line, two branches leading from said main air line, one leading into the air inlet chamber and the other by-passing the said housing, a valve in each of said branches, a smoke discharge line leading from said smoke discharge chamber into said air by-pass branch, and a control for opening one of said valves while simultaneously closing the other valve in the said branches.

11. A smoke generator comprising a housing, a support in said housing for a bed of sawdust, baffles in said housing disposed near the ends thereof defining an air inlet chamber near one end of the housing, a smoke discharge chamber

5 near the opposite end of the housing and an intermediate sawdust containing chamber, a main air line, two branches leading from said main air line, one leading into the air inlet chamber and the other by-passing the said housing, a valve in each of said branches, a smoke discharge line leading from said smoke discharge container into said air by-pass branch, a temperature responsive element in the branch leading into the air inlet chamber, a temperature responsive element in the smoke discharge line, and a control actuated by said temperature responsive elements for opening one of said valves while simultaneously closing the other valve in the said branches.
